FELT-TIGHTENER FOR PAPER-MAKING MACHINES.

1,172,435.

Specification of Letters Patent.

Patented Feb. 22, 1916.

Application filed September 2, 1915. Serial No. 48,673.

To all whom it may concern:

Be it known that I, BENJAMIN DENVER COPPAGE, a resident of Wilmington, Delaware, (whose post-office address is care of

5 The Pusey & Jones Company, Wilmington, Delaware,) have invented a new and useful Improvement in Felt-Tighteners for Paper-Making Machines, which invention is fully set forth in the following specification.

10 The present invention is an improvement in tighteners for felts on paper-making machines, and the object of the invention is to provide a device of the character described which will be simple in construction, which 15 will operate with the minimum of friction, which will be automatic in its action, and which will subject the felt at all times to uniform tension, to the end that the strain on the felts and on the various rolls is reduced to a minimum, and which will insure 20 the proper drying of the paper.

The dry part of a paper-making machine usually consists of a plurality of steam-heated cylinders around each of which is passed 25 a felt or a number of felts, depending upon the class of machine and the kind of paper it is intended to make. In some types of dry parts intended for handling heavy paper or board, no felts are used. Where felts are 30 required, they are used in order to secure intimate contact between the paper to be dried and the steam-heated surface of the driers around which the paper is passed. In order to secure proper contact of the paper 35 with the surfaces of the steam-heated cylinders, proper felt tension is necessary, inasmuch as the paper passes between the felt and the drier cylinders.

40 Paper passing through the dry part of a paper-making machine shrinks both longitudinally and laterally; that is, the paper grows shorter as it becomes drier. On the other hand, the so-called felt, which in the dry part of a paper-making machine is composed 45 of canvas or cotton, grows shorter as it becomes wetter, and longer as it becomes drier. This tendency to lengthen and shorten is most noticeable and greatest when the paper breaks; that is, the felt grows 50 longer when it runs directly against the driers with no paper between, at which time it becomes drier and longer. In modern machines, these felts sometimes lengthen at the rate of ten to fifteen feet per minute when 55 the felt comes into direct contact with the drying cylinders. When wet paper comes

between the felt and the driers, the felt becomes saturated, and therefore shorter, automatically making for the desired tension which brings the paper into intimate contact with the drier surfaces. The shrinking of the felt would, however, be destructive to itself or to the rolls around which it travels, if there were not provided a mechanism which would allow for the shrinkage, 60 this mechanism also acting as a tightener to take up the slack in the felt when the latter lengthens. It is, accordingly, of the greatest importance that this mechanism should be as sensitive as possible and that, to this end, 65 it should operate with the minimum of friction.

The present invention consists in an arrangement of parts which operates with great certainty, sensitiveness and minimum 70 of friction, and maintains a predetermined tension upon the felt, this tension operating uniformly throughout the entire width of the felt.

The invention will be better understood by 75 reference to the accompanying drawing, illustrating one expression of the inventive idea, and wherein—

Figure 1 is a plan view of the felt-tightener of the present invention; Fig. 2 is a side 80 view in elevation; and Fig. 3 is a transverse sectional view on the line 3—3 of Fig. 1.

Referring to the drawings, wherein like reference numerals indicate like parts, 5—5 indicate the dry part frame on which are 85 mounted parallel tracks or ways 6—6 on each of which runs a wheel 7. Each of these wheels 7—7 rotates on a bearing piece or sleeve 8 (one of which is shown in Fig. 3), a roller-race 9 being preferably interposed 90 between said wheels and sleeve. A plurality of standards 10, here shown as four in number, are carried by the frame 5, two on each side of the frame, the standards on the right hand side supporting an upper rail 11, and 95 those on the left hand side of the machine a similar rail 11'. The rails 11 and 11' are engaged by wheels 12 which are also mounted on bearing sleeves 8, a ball-race 13 being interposed between each wheel and bearing. 100 Wheels 12 rotate independently of wheels 7, for a reason hereinafter stated. The balls 9 and 13 are held in place by suitable means, as washers 14.

Through each bearing sleeve or piece 8 110 projects one of the two journals 15 with which a roller 16 is provided, said journals

being securely held in place in said bearings by collars 16', but freely rotating in said sleeves. A felt 17 passes around this roller 16, and the lengthening or shortening of said felt, by the wetting or drying of the same, results in a movement of said roller along the tracks or ways. Suitable means are provided for automatically moving the roller 16 to take up slack in the felt 17; and preferably around each bearing sleeve or piece 8 there is arranged a shackle 18 (Fig. 3) each shackle being provided with a screw-threaded rod 19 which carries nuts 20 and 21 between which are clamped a stirrup piece 22.

15 To each stirrup piece is attached, by suitable means, as pin 23, one end of a chain or connection 24, to the other end of which is secured an adjustable weight 25. Each chain or connection 24 passes over a suitable 20 sprocket wheel 26, one of which is mounted on each end of a shaft 27 provided with journals 28 that are carried by brackets 29 and 30 supported on the frame 5.

The weights 25, preferably one on each 25 side of the device as shown, are of suitable size to tighten the felt the desired amount. Sometimes the felt is longer on one edge than the other, and therefore it frequently happens that the roll 16 is operated to 30 vantage cut of square. This can be effected by adjusting nuts 20 and 21 on one side of the machine.

The construction described results in a 35 tightener which is very sensitive and highly efficient in operation, the pull on the felt being uniform throughout its width. Wheels 7, engaging the lower tracks can rotate in one direction, while wheels 12, engaging the upper tracks are, at the same time, rotating 40 in the opposite direction, this independent mounting and rotation of wheels 7 and 12 permitting bodily movement of the roller 16 with a minimum of friction. This construction can be readily introduced into, and effectively used in, existing installations, and whether the position of the felt is such as to cause the wheels to bear stronger on the upper or lower rails. In the construction illustrated the sprocket wheels 26 are 45 slightly elevated with respect to the points of attachment of chains 24 with pins 23, with the result that the pull of the weights 25 tends to lift the wheels 7 slightly off the lower tracks 6. The shaft 27 is made rigid 50 enough to prevent undue torsion.

While for the purpose of illustration, one expression of the inventive idea has been shown and illustrated in considerable detail, it is to be understood that the invention is 60 not limited to the construction shown, but that the inventive idea is susceptible of various mechanical expressions within the limits of the appended claims.

What is claimed is:—

65 1. In a device of the character described,

a roll provided with a journal at each end, a pair of wheels carried by each journal, a lower track for one wheel of each pair, an upper track for the other wheel of each pair, a bearing interposed between each journal 70 and its wheels, and gravity-actuated means for displacing said roll along said tracks.

2. In a device of the character described, a roll provided with a journal at each end, a pair of wheels carried by each journal, a lower track for one wheel of each pair, an upper track for the other wheel of each pair, a bearing interposed between each journal 75 and its wheels, a weight for each bearing, and connections between said weights and 80 bearings.

3. In a device of the character described, a roll provided with a journal at each end, a pair of wheels carried by each journal, a lower track for one wheel of each pair, an upper track for the other wheel of each pair, a bearing interposed between each journal 85 and its wheels, a weight for each bearing, and connections between said weights and 90 bearings, said connections passing over wheels slightly elevated with respect to the point of attachment between said connections and bearings.

4. In a device of the character described, a roll provided with a journal at each end, 95 a pair of wheels carried by each journal, a lower track for one wheel of each pair, an upper track for the other wheel of each pair, a bearing interposed between each journal and its wheels, a weight for each bearing, a chain connecting each bearing and its 100 weight, and a chain sprocket for each chain slightly elevated with respect to the point of attachment between each chain and its bearing.

105 5. In a device of the character described, a roll provided with a journal at each end, a pair of wheels carried by each journal, a lower track for one wheel of each pair, an upper track for the other wheel of each pair, a bearing interposed between each journal 110 and its wheels, a roller-race interposed between each wheel and its bearing, and gravity-actuated means for displacing said roll along said tracks.

115 6. In a device of the character described, a roll provided with a journal at each end, a pair of independently rotatable wheels carried by each journal, a lower track for one wheel of each pair, an upper track for the other wheel of each pair, and means for displacing said roll along said tracks.

120 7. In a device of the character described, a roll provided with a journal at each end, a pair of independently rotatable wheels carried by each journal, a lower track for one wheel of each pair, an upper track for the other wheel of each pair, and means automatically displacing said roll along said 125 tracks.

8. In a device of the character described, a roll provided with a journal at each end, a pair of independently rotatable wheels carried by each journal, a lower track for one wheel of each pair, an upper track for the other wheel of each pair, and gravity-actuated means for displacing said roll along said tracks.

9. In a device of the character described, 10 a felt, a roll around which the felt passes, a pair of independently rotatable wheels provided at each end of the roll, a lower track for one wheel of each pair, an upper track for the other wheel of each pair, and means 15 for displacing said roll along said tracks.

10. In a device of the character described, a roll provided with a journal at each end, a wheel carried by each journal, a track for

each wheel, a sleeve interposed between each journal and wheel, a member associated with each sleeve, and gravity-actuated means connected to said members. 20

11. In a device of the character described, a roll provided with a journal at each end, a wheel carried by each journal, a track for 25 each wheel, a sleeve interposed between each journal and wheel, a member surrounding each sleeve, and gravity-actuated means connected to said members.

In testimony whereof I have signed this 30 specification in the presence of two subscribing witnesses.

BENJAMIN DENVER COPPAGE.
